US0D1107165S

(12) **United States Design Patent** (10) Patent No.: **US D1,107,165 S**
(45) Date of Patent: ** Dec. 23, 2025

(54) **RIFLE SUPPRESSOR**

(71) Applicant: **Angstadt Arms, LLC**, Charlotte, NC (US)

(72) Inventors: **Richard Adam Angstadt**, Charlotte, NC (US); **Daniel Aaron Smith**, Charlotte, NC (US)

(73) Assignee: **Angstadt Arms, LLC**, Charlotte, NC (US)

(**) Term: **15 Years**

(21) Appl. No.: **29/955,697**

(22) Filed: **Aug. 2, 2024**

(51) LOC (15) Cl. **22-01**

(52) U.S. Cl.

USPC **D22/108**

(58) **Field of Classification Search**

USPC D22/108

CPC F41A 21/02; F41A 21/38; F41A 21/30

(74) Attorney, Agent, or Firm — Schwartz Law Firm, P.C.

(57) **CLAIM**

The ornamental design for a rifle suppressor as shown and described.

DESCRIPTION

FIGS. 1 and 2 are front perspective views of the rifle suppressor;

FIGS. 3 and 4 are rear perspective views thereof;

FIG. 5 is a side view thereof;

FIG. 6 is a rear end view thereof; and,

FIG. 7 is a front end view thereof.

The portions of the rifle suppressor shown in broken-lines form no part of the claimed design.

1 Claim, 5 Drawing Sheets
